PORTABLE KINESCOPE JIG FOR TESTING TELEVISION TUBES

Cecil L. Marshall, 406 Brewer Drive,
Greenwood, Ind. 46142

Filed Sept. 9, 1966, Ser. No. 3,795

Term of patent 14 years

(Cl. D26—1)

Fig. 1.

Fig. 2.

FIG. 1 is a front perspective view of a portable kinescope jig for testing television tubes, showing my new design;

FIG. 2 is a rear perspective view thereof.

The dominant features of my design reside in the portions shown in full lines.

I claim:

The ornamental design for a portable kinescope jig for testing television tubes, as shown and described.
